FLEXIBLE POCKET RECEPACLE

Douglas J. Broughton, Springfield, Mass., assignor
to Buxton, Incorporated, Springfield, Mass., a
corporation of Massachusetts

Application August 9, 1945, Serial No. 609,817

7 Claims. (Cl. 150—30)

1

This invention relates to an improvement in the construction of billfolds formed of leather or other flexible materials.

Such billfolds customarily comprise front and rear walls variously connected along their bottom and end edges to provide a bill compartment open along its upper edge. The end sections of the billfold are foldable one on the other about a substantially central line of fold. One or both end sections of the front wall are customarily provided with auxiliary pockets opening toward the fold line for the reception of cards and the like. Since the inner wall tends to buckle at the line of fold when the end sections of the billfold are folded together it is desirable to construct the front wall to permit a limited lengthwise expansion and contraction. One customary and desirable way of providing such expansion and contraction is to include as one element of the front wall an intermediate wall member at least one end of which is telescopically slideable in the members making up the end sections of the front wall. When the bill compartment of the billfold, or the auxiliary pockets, or both, are filled to, or approximating, their capacity there is a tendency to bind the intermediate wall member thereby preventing or interfering with its freedom of sliding movement with respect to the other members of the front wall. This is particularly true with respect to the stuffing of the auxiliary pockets, which has for some time been a growing habit of billfold users.

The principal object of my invention is to overcome these difficulties and at the same time increase the capacity of the billfold particularly with respect to the auxiliary pockets. This object is accomplished by a particular inclusion and arrangement of gusset members in the construction of the billfold. I am of course aware that gussets have been variously applied to pockets generally to increase their capacity and that attempts have been made to apply them for increased capacity to billfold pockets, but as far as I am aware such attempts have tended to increase the difficulties mentioned and I know of no previous suggestion that gussets could be used in a manner to overcome these difficulties or of any gusset arrangement which secured that effect.

The application of gussets to billfold pockets having in view merely an increase in pocket capacity have heretofore proved unsatisfactory as a practical matter. I believe one reason for this failure to be that when gussets are applied in the conventional manner the result is to stiffen and tighten the whole structure whereas a certain degree of looseness and flexibility permitting self adjustments between the several parts of the billfold are essential if the billfold is to function properly.

It is therefore a further object and advantage

10

5

of my invention to provide a gusset construction for billfold pockets which will function to increase the pocket capacity per se, at the same time that increased freedom is afforded the intermediate wall member.

Other and further objects and advantages residing in the details of the construction will be made apparent in the following specification and claims.

In the accompanying drawings,

Fig. 1 shows the form of a blank from which the body of a billfold embodying my invention may be constructed;

Fig. 2 is a plan view of the intermediate wall member which with the elements of the blank shown in Fig. 1 complete the members of a billfold embodying my invention;

Figs. 3 and 4 are fragmentary views on a larger scale showing certain of the folding and assembling steps in constructing the billfold from the parts shown in Figs. 1 and 2;

Fig. 5 is a front elevational view, on the scale of Fig. 1, showing the completed billfold, parts being broken away;

Fig. 6 is a fragmentary, generally perspective view of the billfold of Fig. 5 on a larger scale;

Fig. 7 is a view similar to Fig. 6 but showing the bill compartment gusset omitted;

Fig. 8 is a fragmentary view of a blank similar to Fig. 1 but showing a modified arrangement;

Fig. 9 is a fragmentary generally perspective view, on a larger scale, parts being broken away, showing the arrangement of the parts in the billfold made up from the blank of Fig. 8;

Fig. 10 is a fragmentary view of a blank similar to Fig. 8 but showing a further modification;

Fig. 11 is a fragmentary generally perspective view, on a larger scale, parts being broken away, showing the arrangement of the parts in the billfold made up from the blank of Fig. 10;

Fig. 12 is a sectional view substantially on the line 12—12 of Fig. 11;

Figs. 13 to 17 inclusive show the several of the elements of a billfold embodying my invention formed as separate pieces arranged for blind stitching;

Figs. 18 and 19 are fragmentary generally perspective views, on a larger scale, showing steps in the construction of a billfold using the blanks shown in Figs. 13 to 17; and

Fig. 20 is a sectional view substantially on line 20—20 of Fig. 19 but showing the elements in completed position.

It will be understood that the drawings are not to scale and that the relative thickness of the material has been exaggerated in the interest of clearness.

In the illustrative embodiment shown in Fig. 1 and the other figures the billfold includes a rear wall 1, spaced panel members 2, flap mem-

bers 3, and closure members 4, and an intermediate wall member 5 (Fig. 2). As shown the billfold preferably includes partition members 6 which carry closure flaps 7.

Each panel member 2 is connected to the lower or bottom edge of the rear wall by a gusset member 8 comprising inner and outer elements 9 and 10. Flap member 3 is connected to the opposite edge (in the finished billfold this is the upper edge) of its panel 2 by a gusset 11 comprising inner and outer elements 12 and 13 respectively. As shown in Fig. 1, for example, end closure members 4 are connected to the ends of rear wall 1 by gussets 14, comprising inner and outer elements 15 and 16.

For reasons later discussed in connection with Fig. 6 the gussets 14 may in many cases be omitted without substantial detriment to achieving certain objects of the invention.

The partition member 6 is connected, integrally in Fig. 1, directly to the outer end edge of panel 2.

Preferably the upper and lower edges of the rear wall 1 are provided with tabs 17 and 18 respectively which are folded over and cemented or otherwise secured to the rear wall, to "finish" the exposed edges of the wall, in a well known manner.

The flaps 3 are each provided at their outer ends with lock tabs 19 adapted to engage, as later described, in slots 20 formed in panels 2. The end members 4 are each provided with lock tabs 21 engageable in slots 22 also formed in the panels 2. Flaps 3 are formed with slots 23 in which tabs 24, formed on the upper edge of intermediate wall member 5 (Fig. 2) are engaged all as later described.

As shown the billfold is symmetrical and a description of the folding and assembly of one end will serve to describe both, it being understood that the folding and assembly of both ends will preferably proceed together.

Referring to Fig. 3, the partition member 6 is shown folded over on the adjacent panel 2 and the gussets 8 and 11 are folded on top of the partition member. As also shown in said figure the gusset 14 is folded onto the rear wall 1.

The panel 2 is then folded onto the rear wall as shown in Fig. 4, the intermediate wall member 5 being placed between the gussets 8—11 and the rear wall with its lower edge engaged in the bight between the inner gusset element 9 and wall 1. Flap 3 is then folded downwardly between wall 1 and the intermediate wall member 5 with the upper edge of the intermediate member engaging in the bight between the inner gusset element 12 and flap 3. The tabs 24 on the member 5 are inserted through slots 23 (as shown in Figs. 6 and 9) and the lock tabs 19, see Fig. 4, are folded over on panel 2 and inserted in slots 20. The end members 4 are then folded over onto panel 2 and lock tabs 21 engage in slots 22 to complete the setting up of the billfold as shown in Fig. 5, which shows both ends of the billfold completed. It will be understood that any other suitable means for connecting the ends of the rear wall to the panel members may be employed in place of the end members 4 and lock tabs 21.

Any suitable means may be employed for holding the closure flaps 7 closed, that shown comprising tongues 25 engageable in slots 26 which are provided with entrance pieces 27 in accordance with the disclosure of Buxton Patent 2,318,750.

As best shown in Fig. 6 the structure described

provides a bill compartment 28 between rear wall 1 and intermediate wall 5 which is expandable at its ends by reason of gussets 14, which extend into the bill compartment. Also a side pocket 29 is provided between intermediate wall member 5 and panel member 2, which pocket is expandable at the top and bottom by reason of gussets 8 and 11 which extend into the pocket. Restricting pressure of cards, or the like, which may be placed in space 29, against the intermediate wall member 5 is relieved by the gussets 8 and 11. The outer end of pocket 29 is closed by the lock member 19 but since the intermediate member does not extend to the end of the billfold the binding action on the intermediate member is not ordinarily substantial at that point. In practice it has been found that usually the side gussets are sufficient for the purpose of freeing the intermediate wall member from restraint.

For a similar reason the end gussets 14 may frequently be omitted, as shown in Fig. 7, particularly if the flaps 3 do not extend substantially below the longitudinal center of the intermediate wall member 5 as shown in the various figures and as taught in prior Buxton Patent 2,011,846. In either case the fact that the bights of the gussets, which form the runways for the upper and lower edges of the intermediate member, widen in angle as the pocket fills further tends to increase the freedom of movement of the intermediate member. Also the presence of the intermediate wall member in the bights of the gusset tends to hold the gusset in shape and prevent the pocket from sagging—it acts to stiffen and reinforce the edge of the gusset.

The partition member 6, when used, divides the space 29 into two compartments, the outer compartment 30 being closed by the flaps 7 carried by the partitions. As shown in Figs. 6 and 7 the partition members are normally positioned in the outer bights of the gussets 8 and 11. Preferably as is evident in the several figures the partition members are made slightly narrower than the panel members with which they are associated. As perhaps best shown in Figs. 6 and 7 the partition 6 while narrower than its panel 2 is wider than the distance between the inwardly extending folds of the gussets 8 and 11 and its edges are normally confined between the bight of the outer gusset elements 10 and 13 and the panel 2. By narrowing the partition, the latter is permitted a limited swing toward and from the panel member so that, depending on the extent to which the partition is narrowed, the compartment 30 shares the expansion resulting from the outer gusset elements 10 and 13. The combined capacities of the compartments 29 and 30 are limited by the expansion of the gussets and if the load placed or desired to be placed in compartment 30 exceeds half of the combined capacity of the two pockets the partition member will be, or can be forced past the inwardly extending fold of the gusset so that the major portion of the gusset will operate in compartment 30. In whatever position the partition is placed the gussets act to relieve the pressure of the contents of the pockets against the intermediate wall member and do this without interfering with the flexibility of the billfold as a whole. The partition member may of course be made sufficiently narrow to swing freely between the opposite gussets.

The structures so far described will for ordinary purposes afford adequate relief to the intermediate wall member 5. In some instances,

however, it is desirable to provide a gusset at the end as well as the sides of the space 29. Such desirability may arise for example when the user desires to carry an address book or a flat compact in one of the billfold pockets. One way of accomplishing this is to position one of the end gussets 14 in the space 29 as shown in Figs. 8 and 9. When this is desired the flap 3 cannot satisfactorily be secured to the panel 2 by the lock member 19 as previously described except by gusseting the member 19 which would result in an undesirable thickening at the end of the billfold as well as an undesirable degree of looseness between flap 3 and the other elements of the billfold. These difficulties are overcome in the preferred construction of Figs. 8 and 9 where flap 3 is shown provided with a tongue 31 adapted, when the parts are set up as shown in Fig. 9, to extend through a slot 32 formed substantially at the juncture of inner gusset element 15 and wall 1. The tongue 31 is formed with shoulders 33 which prevent inward movement of the tongue. The tongue 31 is provided with one element of a snap fastener 34 adapted to engage another fastener element, not shown, on the opposite end portion of wall 1, to hold the billfold in folded condition. As will be apparent from Fig. 9 the tongue 31 holds flap 3 in desired position while all three gusset members 8, 11, and 14 operate in the space between member 5 and panel 2.

Figs. 10, 11, and 12 show a modification of the structure of Figs. 8 and 9 to provide maximum relief of the intermediate wall member in a billfold of maximum capacity. As shown in Fig. 10 an additional gusset member 35 comprising elements 36 and 37, is inserted between the end of wall member 1 and element 15 of gusset 14 and slot 32 is positioned at the juncture of element 37 of gusset 35 with element 15 of gusset 14. An additional gusset member 38 comprising elements 39 and 40 is also inserted between rear wall 1 and element 9 of gusset 8. The parts are set up, in substantially the manner previously described, to position gusset 38 and gusset 35 (together with the corresponding gussets at the other end of the billfold, not shown) in bill compartment 28, as will be apparent from Figs. 11 and 12. Gussets 8, 11, and 14 are positioned in space 29 as shown in the latter figures. As will be seen the ends of flaps 3 are held by tongue 31 in the bight between gusset elements 15 and 37 with the upper edge of the intermediate wall member 5 riding in the bight between inner gusset element 12 and flap 3 and its lower edge riding in the bight between gusset elements 9 and 40 (Fig. 12).

The pressure on both faces of the intermediate wall member, from the load in the bill compartment as well as from the load in pocket space 29, is thus relieved.

It will be understood that the depth of the gusset member may be varied, depending on the degree to which the billfold is to be loaded, and that the several arrangements shown may be variously combined with each other and with conventional billfold structures to meet particular needs.

In the forms so far described the billfold elements, with the exception of the intermediate wall member 5, are integrally connected together and in the finished billfold the parts are interlocked so as to avoid the need for stitching in holding billfold parts in operative relation. My invention is not to be understood as limited to such a construction and lends itself to the use of stitching and in a manner in which the stitches are hidden. In Figs. 13 to 20 inclusive I have

illustrated one form of a stitched embodiment of my invention.

Figs. 13 to 16 inclusive show the same elements which make up one end of the previously described billfold as separate pieces, the elements between which the gussets are positioned carrying one half of the adjacent gusset. Thus, rear wall member 1 carries element 9, panel 2 carries elements 10 and 13 and flap 3 carries element 12. End closure member 4 and partition member 6 are formed as separate pieces. The several edges that are to be stitched together are provided with narrow extensions 55 to receive the stitching.

The rear wall 1, panel 2 and flap 3 are stitched together as shown at 56 in Fig. 18. The flap 3 and panel 2 are then folded up as shown in Fig. 19 bringing the extended edge portions 55 of the rear wall and flap 3 into superposed relation. As clearly shown in Fig. 19 the sewing edge 55 of partition member 6 is placed over the superposed sewing edges of wall 1 and flap 3 and the sewing edge of member 4 is placed beneath the sewing edge of the rear wall and all are stitched together by a single line of stitching 57. The partition member 6 is then inserted through the tube formed between the rear wall 1 and panel 2 to draw the stitched connection into the tube as shown in Fig. 20. End member 4 is then folded onto panel 2 as shown in the latter figure and interlocked as previously described. Intermediate member 5 may be inserted at any convenient step in setting up the billfold as when the parts are in the condition shown in Fig. 19 or after the billfold is otherwise completed. As will be obvious all of the stitches lie within the space between the panel member 2 and the intermediate wall member 5 and are thereby completely hidden.

It will be understood that the several arrangements shown may be variously combined to meet specific needs. In each case the positioning of the upper and lower edges of the intermediate member in bights of the gussets provide expansible guideways for said member which guideways expand to decrease the grip of the guideways as the pocket space between the intermediate wall member and the panel is loaded. Also in each case the positioning of inwardly extending gusset elements in the space between the intermediate member and the panel, whether a partition member is present or not, acts to release the direct pressure of the load in the pocket against the outer face of the intermediate member. These desired objectives and advantages together with an increase in the capacity of the billfold are obtained without substantially impairing the general flexibility of the structure as a whole.

I claim:

1. In a billfold having a rear wall and a front wall assembly providing a bill compartment between them, the front wall assembly including a panel member having a flap, said flap extending downwardly into the bill compartment; the outer end edge of said flap and the adjacent end edge of the rear wall being respectively provided with sewing extensions superposed one on the other, an end closure member having a sewing extension, said last named extension being superposed on the sewing extension of the rear wall on the opposite side from the sewing extension of the flap, the free edges of the three extensions substantially coinciding, stitches connecting the so superposed sewing extensions, said stitches passing through the sewing extensions only, and means connecting the end closure member to

the outer face of the panel member to close the end of the billfold and position the sewing extensions, and the stitches connecting them, inwardly of the billfold.

2. In a billfold having a rear wall and a front wall assembly providing a bill compartment between them, the front wall assembly including a panel member having a flap, said flap extending downwardly into the bill compartment, and an intermediate wall member; the outer end edge of said flap and the adjacent end edge of the rear wall being respectively provided with sewing extensions superposed one on the other, an end closure member having a sewing extension, said last named extension being superposed on the sewing extension of the rear wall on the opposite side from the sewing extension of the flap, the free edges of the three extensions substantially coinciding, a partition member having an edge superposed on the said extensions on the side opposite the end closure member with the body of the partition member extending away from the free edges of said extensions, stitches connecting said extensions and the superposed edge of the partition member together, said stitches passing through the sewing extensions only, and means connecting the end closure member to the outer face of the panel member to close the end of the billfold and position the sewing extensions, and the stitches connecting them inwardly of the billfold with the partition member extending inwardly between the intermediate wall member and the panel member.

3. In a billfold having a rear wall and a front wall assembly providing a bill compartment between them, said assembly including a panel member and a member intermediate the panel member and the rear wall, the panel member having a flap extending downwardly into the bill compartment between the rear wall and said intermediate member; an inwardly extending gusset connecting the upper edge of the panel member to said flap, an inwardly extending gusset connecting the lower edge of the panel member to the rear wall, the intermediate member being interlocked with said flap to slidably hold the upper and lower edges of the intermediate member, respectively, in the bight between the first gusset and the flap and the bight between the second gusset and the rear wall, and an end member extending from the end edge of the rear wall and folded over onto the panel member and interlocked therewith to close the outer end of the bill compartment and the outer end of the pocket formed between the intermediate member and the panel and to hold the gussets in said last-named pocket and limiting the degree of expansion allowed the outer ends of the gussets.

4. In a billfold having a rear wall and a front wall assembly providing a bill compartment between them, said assembly including a panel member and a member intermediate the panel member and the rear wall, the panel member having a flap extending downwardly into the bill compartment between the rear wall and said intermediate member; an inwardly extending gusset connecting the upper edge of the panel member to said flap, an inwardly extending gusset connecting the lower edge of the panel member to the rear wall, the intermediate member being interlocked with said flap to slidably hold the upper and lower edges of the intermediate member, respectively, in the bight between the first gusset and the flap and the bight between the second gusset and the rear wall, a partition mem-

ber extending from the outer end edge of the panel member and folded over the inner face of the panel member with its longitudinal edges engaged in the bights between the gussets and the panel member, and an end member extending from the end edge of the rear wall and folded over onto the panel member and interlocked therewith to close the outer end of the bill compartment and the outer end of the pocket formed between the intermediate member and the panel and to hold the gussets in said last-named pocket and limiting the degree of expansion allowed the outer ends of the gusset.

5. In a billfold having a rear wall and a front wall assembly providing a bill compartment between them, said assembly including a panel member and a member intermediate the panel member and the rear wall, the panel member having a flap extending downwardly into the bill compartment between the rear wall and said intermediate member; an inwardly extending gusset connecting the upper edge of the panel member to said flap, an inwardly extending gusset connecting the lower edge of the panel member to the rear wall, the intermediate member being interlocked with said flap to slidably hold the upper and lower edges of the intermediate member, respectively, in the bight between the first gusset and the flap and the bight between the second gusset and the rear wall, an end member extending from the end edge of the rear wall and folded over onto the panel member and interlocked therewith to close the outer end of the bill compartment and the outer end of the pocket formed between the intermediate member and the panel, said end member being connected to the rear wall by an inwardly extending gusset and means including an interlocking tongue extending from the end edge of said flap for holding the flap and the intermediate member in a bight of the last-named gusset.

6. A billfold as in claim 5 in which said tongue is interlocked to the outer face of the panel member to position the flap and intermediate member in that bight of the end gusset which is adjacent the panel member, and position the end gusset in the bill compartment.

7. A billfold as in claim 5 in which said tongue is interlocked in that bight of the end gusset which is adjacent the rear wall to position the flap and intermediate member in the last-named bight and position the end gusset in the pocket between the intermediate member and the panel member.

DOUGLAS J. BROUGHTON.
